(57) **CLAIM**

The ornamental design for a “pressure washer”, as shown and described in FIGS. 1-8.

DESCRIPTION

FIG. 1 is a front, right perspective view of a pressure washer. FIG. 2 is a rear, left perspective view of the pressure washer of FIG. 1.

FIG. 3 is a left, front perspective view of the pressure washer of FIG. 1.

FIG. 4 is a right view of the pressure washer of FIG. 1.

FIG. 5 is a left view of the pressure washer of FIG. 1.

FIG. 6 is a rear view of the pressure washer of FIG. 1.

FIG. 7 is a front view of the pressure washer of FIG. 1; and, FIG. 8 is a top view of the pressure washer of FIG. 1.

The features shown in broken lines form no part of the claimed design.

The lighter solid lines denote surfaces and contours. Line shading is not surface ornamentation.

1 Claim, 8 Drawing Sheets(56)
